UNITED STATES PATENT OFFICE

138,495

DESIGN FOR A CRIBBAGE BOARD

Ernest H. Hall, St. Paul, Minn.

Application March 31, 1944, Serial No. 113,096

Term of patent 14 years

(Cl. D34—5)

To all whom it may concern:

Be it known that I, Ernest H. Hall, a citizen of the United States, residing at St. Paul, in the county of Ramsey and State of Minnesota, have invented a new, original, and ornamental Design for a Cribbage Board, of which the following is a specification, reference being had to the accompanying drawing, forming a part thereof.

In the drawing:

Fig. 2 is a part vertical section taken on the line 2—2 of Fig. 1 and part side elevational view of the same.

I claim:

The ornamental design for a cribbage board, as shown.

ERNEST H. HALL.
